UNITED STATES PATENT OFFICE.

PAUL PETZOLD, OF GERA, GERMANY,

MACHINE VISE.

Application filed October 6, 1923. Serial No. 666,997.

To all whom it may concern:

Be it known that I, PAUL PETZOLD, a citizen of Germany, residing at Gera (Reuss), Untermauserstr. 58, Germany, have invented certain new and useful Improvements in Machine Vises (application for which has been filed in Germany, July 20, 1921), of which the following is a specification.

This invention has reference to machine vises, and in particular to devices of this kind in which the carriage on which the clamping jaws are mounted is disposed so as to be rockable on a vertical and a horizontal axis. With this form of construction of the vise the piece of work may be easily adjusted in any desired inclined position, and without in any way altering the position of the piece of work between the clamping jaws. It is a further object of my invention to provide a vise of this kind adaptable for work requiring very high stresses, and in view thereof in a preferred form of construction I provide a carriage having substantially the shape of a cylindrical segment and on which trunnions are arranged coaxially disposed with relation to the cylindrical surface, the said cylindrical segment being preferably supported by a trough shaped foundation rotatable on a vertical axis upon the machine base, and provided with bearings coaxially disposed with relation to the curvature of the supporting foundation, and adapted for the journaling of the trunnions of the carriage or slide. Other important objects and advantages of my invention will appear as the specification proceeds and from an inspection of the drawings.

An embodiment of the principles of my invention is shown by way of example on the accompanying drawing in Figure 1 in side view and partly in vertical longitudinal section; Figure 2 is a plan view; Figure 3 is a side elevation and Figure 4 is a vertical cross section on the broken line A—B—C—D.

Upon the base plate *a* a trough shaped foundation support *b* is mounted so as to be rotatable upon the vertical central axis. In the base plate *a* there is provided a cylindrical recess *c* into which a cylindrical projection *d* of the foundation *b* is adapted to enter. The connection of the foundation *b* with the base plate *a* is effected by two screws *e* the heads of which are movable in

a circular annular recess *f* of the base plate *a*. Two holes *g* are provided in the base plate for the insertion of the screws. The trough shaped foundation *b* is provided with a flanged portion *h* which in the preferred form of construction may carry a graduated scale.

The support or foundation *b* at both of its ends constitutes a bearing *i* coaxially disposed with relation to the curvature of the foundation *b*. In the bearings *i* and by means of the studs or trunnions *k* the slide or carriage *m* is mounted provided with the jaws *n*, and consisting of a cylindrical segment *o* supported upon the trough shaped foundation, and also comprising two upwardly directed portions *p* on which the trunnions *k* and a frame *q* are arranged. Upon the longitudinal sides of the frame *q* the jaws *n* are arranged which are secured by plates *r* against being lifted off from the frame *q*, the sides of the frame preferably partially engaging their vertical sides. A spindle *s* with right and left handed screw threads serves for the adjustment of the jaws and is provided at each of its ends with a four-cornered head for the engagement of a wrench, key or the like. Recesses *k'* are provided in the trunnions *k* for facilitating the engagement of the key or the like with the heads.

A graduated scale *t* is provided for determining the amount of rocking of the carriage upon its horizontal axis which coincides with the axis of the shaft or spindle *s*. The screws *e* serve for the locking of the foundation *p* in position after its adjustment around the vertical axis. The screws *y* serve for the locking in position of the trunnions *k*. In order to effect the adjustment in the most convenient manner the supporting foundation *b* may be provided with a worm wheel *u* adapted to be engaged with a spindle *v*, and in a similar manner one of the trunnions *k* may be provided with a worm wheel *w* engageable with a spindle *x*.

It is to be understood that the invention is not confined to the particular embodiment herein shown and described merely by way of example and for the purposes of illustration and explanation, but it is susceptible of various other embodiments and modifications to adapt the invention to varying conditions and to the convenience of the op-

erator, and without deviating from the spirit of my invention as pointed out in the appended claims.

I claim:—

- 5 1. In a machine vise, in combination, a cross sectionally segmental carriage, a substantially trough shaped rotatable support for said carriage, bearing and journaling means on said carriage concentrically disposed with relation to the curvature thereof, trunnions coaxially arranged on said segmental carriage, and journalled in said bearing means, and means to lock the carriage and the support in the adjusted positions.
- 10 2. In a machine vise, in combination, a rockingly and rotatably supported carriage, bearing means for said carriage, an adjusting spindle on said carriage coaxially disposed relatively to said bearing means, clamping means operatively connected to said spindle, a substantially rectangular frame on said carriage and connected to the
- 15
- 20

bearing means, and partially embracing said clamping means.

3. In a machine vise, in combination, a 25 rockingly and rotatably supported carriage, bearings means on said carriage, a substantially rectangular frame connecting said bearing means, clamping means displaceably mounted on the longitudinal sides of said frame, means on said frame, engageable with the vertical sides of said clamping means, an adjusting spindle coaxially mounted in said bearing means and in operative engagement with said clamping 30 35 means.

In testimony whereof I have signed my name to this specification in the presence of two subscribing witnesses.

PAUL PETZOLD.
